C. A. ROBERTSON

LUBRICATOR

Filed March 24, 1924.

UNITED STATES PATENT OFFICE.

CHARLES A. ROBERTSON, OF JACKSON, MICHIGAN, ASSIGNOR TO MONTGOMERY WARD & COMPANY, OF CHICAGO, ILLINOIS, A CORPORATION OF ILLINOIS.

LUBRICATOR.

Application filed March 24, 1924. Serial No. 701,262.

To all whom it may concern:

Be it known that I, CHARLES A. ROBERTSON, a citizen of the United States, residing at Jackson, in the county of Jackson and State of Michigan, have invented certain new and useful Improvements in Lubricators, of which the following is a specification.

The present invention has for its primary object the provision of a lubricator of the gravity feed type designed for use particularly with internal combustion engines, and of such construction as to insure proper feeding of the lubricant against the pressure due to the explosion of the combustible mixture.

In the ordinary construction of this type of lubricator as commonly employed with explosive engines, the gases from the cylinder find their way into the feed tube of the lubricator. This pressure from the explosives thus arising impedes the feed of the lubricant, and the latter is prevented having proper access to the interior of the cylinder. To avoid this is the purpose of the herein-described invention, its aim being to provide simple and efficient means for insuring passage of the lubricant from the cup to the interior of the cylinder freed from the back pressure of the gases, and thereby capable of movement without interference by such back pressure.

A further object of the invention is the provision of means for relieving the lubricator of the accumulation of the gases so that liability of the lubricator being rendered inoperative, due to the pressure of the accumulated gases, is eliminated.

Other objects and advantages of the invention will appear as the nature of the improvements is better understood, the invention consisting substantially in the novel construction, combination and arrangement of parts hereinafter fully described, illustrated in the accompanying drawings, and finally pointed out in the appended claims.

It is to be understood that the form of the invention herein shown and described is an expression of but one embodiment thereof, and such disclosure is to be taken merely in an illustrative rather than a restrictive sense.

In the drawings,

Fig. 1 is a vertical sectional view of a lubricator constructed in accordance with the present invention and illustrated in applied relation to an explosive engine;

Fig. 2 is a sectional plan view on the line 2—2, Fig. 1.

Referring now in detail to the accompanying drawings, the numeral 10 designates an internal combustion engine of any approved type, that illustrated being one of the small power engines designed for use in and about the farm, and thus handled by persons with little skill in the care and maintenance of engines of this sort. It includes the usual water-jacketed cylinder 11 having a supply tank 12 surmounting the same for storage of the cooling water. The cylinder 11 is provided with a port 13 which communicates with the interior thereof, and through which the lubricant is introduced.

The numeral 14 designates the cup of an ordinary gravity feed lubricator which is provided with suitable mechanism for controlling the passage of the lubricant from the cup to the cylinder 11. This forms no part of the present invention, and any cup provided with such mechanism may be utilized. Depending from the lower end of the cup 14 is a feed tube 15 which is suitably connected to the threaded boss 16 at such lower end. The feed tube 15 is of sufficient length to pass down into the port 13 so that its lower end will be in close proximity to the inner end of said port. The diameter of the feed tube 15 is considerably less than the diameter of the port 13, and said feed tube is surrounded by a supporting tube 17

the diameter of which is sufficiently greater than that of the feed tube 15 to provide an annular space 18 between the two tubes. The supporting tube 17 is engaged with the outer end of the port 13, its lower end being open and in communication with the port 13, and connected to the upper end of the supporting tube 17 is an internally threaded coupling sleeve 19. The boss 16 is engaged with the upper end of the sleeve 19 and is spaced sufficiently from the upper end of the supporting tube 17 to provide a relief chamber 20 between that end of the supporting tube 17 and the boss. In communication

with the chamber 20 is a relief port 21, which is formed in one side of the coupling 19, and this port normally is open to the atmosphere. The feed tube 15 passes through the relief chamber 20 so that the lubricant is fed from the cup 14 downwardly through the tube 15 without contact with the conditions prevailing in the relief chamber 20.

10 In the operation of the herein-described lubricator as applied to an explosive motor in the manner hereinbefore described, the controlling mechanism is set for the proper gravity feed of the lubricant from the cup.

15 Due to the length of the feed tube 15, the lubricant freely passes downwardly from the cup to the port 13, whence it drops into said port and into the interior of the cylinder 11. The port 13 being normally in communication with the interior of the cylinder 11, it is apparent that the gases arising incident to the explosion of the charges will enter the port 13, and if no provision were made to conduct these gases from the port 20 accumulation of the same would follow, and thus impede flow of the lubricant into the cylinder. This is what occurs where there is but a single passage between the lubricator and the engine cylinder. In the 30 present instance, however, the space between the supporting tube 17 and the feed tube 15 is in communication only with the port 13, and has no communication with the interior of the cup 14; neither is there communication with the interior of the feed pipe 15 and the space between that pipe and the supporting tube 15. Hence, any gases entering the port 13 pass into the surrounding space between the tube 15 and the tube 17, flow into the relief chamber 20, and then emerge to the atmosphere through the normally open relief port 21. This relieves the interior of the feed tube 15 from the pressure of these gases, and the lubricant is free to flow downwardly therethrough from the cup 14 to the interior of the engine cylinder. Due to the relief port 21, there is no accumulation of the gases in the space between the tubes 15 and 17, this space forming a conduit through which the gases from the cylinder 11 may escape and pass out of the port 21 to the atmosphere.

I claim:

- 55 1. In a lubricator of the class described, the combination with the cup thereof, of a feed tube depending therefrom and in communication with the interior thereof, a conduit surrounding said feed tube and spaced therefrom to provide a passageway between said feed tube and conduit, and means for relieving the interior of said conduit of accumulated pressure.
- 60 2. In a lubricator of the class described, the combination with the cup thereof, of

a feed tube depending therefrom and in communication with the interior thereof, a conduit surrounding said feed tube and providing a passageway between the latter and the conduit, said conduit including a relief chamber, and means for relieving said chamber and conduit of accumulated pressure. 70

3. In a lubricator of the class described, the combination with the cup thereof, of a feed tube depending therefrom and in communication with the interior thereof, a conduit surrounding said feed tube and providing a passageway between the latter and the conduit, said conduit including a relief chamber, the latter being provided with a port normally open to the atmosphere for relieving said chamber and conduit of accumulated pressure. 75

4. In a lubricator of the class described, the combination with the cup thereof, of a feed tube depending therefrom and in communication with the interior thereof, a relief chamber depending from the lower end of the cup and through which said feed tube passes, a conduit connected to said relief chamber and surrounding said feed tube to provide a passageway between the latter and the conduit, and means for relieving said chamber and conduit of accumulated pressure. 80

5. In a lubricator of the class described, the combination with the cup thereof, of a feed tube depending therefrom and in communication with the interior thereof, a relief chamber depending from the lower end of the cup and through which said feed tube passes, a conduit connected to said relief chamber and surrounding said feed tube to provide a passageway between the latter and the conduit, said chamber being provided with a port normally open to the atmosphere for relieving said chamber and conduit of accumulated pressure. 95

6. In an explosive engine, the combination with the cylinder thereof having a port for the admission of lubricant to its interior, of a supporting tube connected to said port, a lubricator cup connected to said conduit, and a feed tube connected to said lubricator cup and extending downwardly therefrom through said supporting tube, the feed tube being of less diameter than the bore of the supporting tube, whereby to provide a passage between said tubes for the gases escaping through said port, and means for relieving said passage of the gases accumulating therein. 110

7. In an explosive engine, the combination with the cylinder thereof having a port for the admission of lubricant to its interior, of a supporting tube connected to said port, a lubricator cup connected to said conduit, a feed tube connected to said lubricator cup and extending downwardly therefrom through said supporting tube, the 115

feed tube being of less diameter than the bore of the supporting tube, whereby to provide a passage between said tubes for the gases escaping through said port, said feed tube being provided with a port normally open to the atmosphere for relieving said passage of the gases accumulating therein.

8. In an explosive engine, the combination with the cylinder thereof having a port for the admission of lubricant to its interior, of a supporting tube connected to said port, a coupling sleeve arranged at the upper end of said tube, a lubricator cup connected to said coupling and spaced thereby from the supporting tube, whereby to

provide a relief chamber between the supporting tube and the lubricator cup, a feed tube connected to said lubricator cup and extending downwardly therefrom through said relief chamber and supporting tube, the feed tube being of less diameter than the bore of the supporting tube, whereby to provide a passage between said tubes for the gases escaping through said port, and means for freeing the relief chamber and the supporting tube of the gases accumulating therein. 20 25

In testimony whereof I have hereunto signed my name.

CHARLES A. ROBERTSON.
